[57] CLAIM

The ornamental design for a combined dimmer, switch, IR receiver, thermostat, ambient light sensor, and passive infrared motion sensor, as shown and described.

DESCRIPTION

FIG. 1 is a front and upper right perspective view combined dimmer, switch, IR receiver, thermostat, ambient light sensor and passive infrared motion sensor showing our new design;

FIG. 2 is a top view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.
